United States Patent Office

Des. 188,866
Patented Sept. 20, 1960

188,866

BRACELET LINK OR SIMILAR ARTICLE

Karl C. Augenstein, Cranston, R.I., assignor to Speidel Corporation, Providence, R.I., a corporation of Rhode Island

Filed June 30, 1959, Ser. No. 56,598

Term of patent 14 years

(Cl. D45—4)

FIG. 1

FIG. 3

Fig. 1 is a top plan view of a bracelet link or similar article showing the new design;

Fig. 2 is a side elevational view of the link shown in Fig. 1; and

Fig. 3 is a side elevational view looking from right to left at the link shown in Fig. 1.

I claim:

The ornamental design for a bracelet link or similar article, substantially as shown.
